UNITED STATES PATENT OFFICE.

HEINRICH KOPPERS, OF ESSEN-RUHR, GERMANY, ASSIGNOR TO THE KOPPERS DEVELOPMENT CORPORATION, A CORPORATION OF PENNSYLVANIA.

COKING RETORT-OVEN.

1,369,673.

Specification of Letters Patent.

Patented Feb. 22, 1921.

Application filed September 10, 1920. Serial No. 409,368.

To all whom it may concern:

Be it known that I, HEINRICH KOPPERS, (assignor to The Koppers Development Corporation, of Pennsylvania,) a citizen of 5 Germany, residing in Essen-Ruhr, Germany, have invented a new and useful Improvement in Coking Retort-Ovens, of which the following is a specification.

This invention relates to the art of making coke, particularly in by-product coke ovens; the invention has for primary objects the production of uniformly high grade coke for metallurgical and other purposes and especially free-burning coke suitable for 10 blast furnace operations and also free-burning coke for domestic use, and also to produce such free-burning coke in a short coking time, and at lower temperatures than that required by ordinary processes.

20 The invention has for further objects such other improvements or advantages in operation and such other advantageous results as may be found to obtain in the improved processes and apparatus hereinafter described as illustrative examples.

25 In the accompanying drawings, forming a part of this specification, and showing, for purposes of exemplification, a preferred manner in which the invention may be embodied and practised, but without limiting the claimed invention specifically to such 30 illustrative instance or instances:

Figure 1 is a diagrammatic perspective and sectional view of a by-product coking 35 retort oven for carrying out the improvements of the invention;

Fig. 2 is a view similar to Fig. 1, but illustrating a further development of the invention;

40 Fig. 3 is a diagrammatic sectional view through a coking chamber of a coking retort oven and illustrates other parts hereinafter more fully described;

Fig. 4 is a detailed transverse section of a 45 modified form of channeling means;

Fig. 5 is a vertical section through the heating wall of a coking retort oven illustrating a further embodiment of the invention;

50 Fig. 6 is an enlarged vertical sectional elevation through the bottom of a coking chamber of the oven illustrated in Fig. 5;

Fig. 7 is a horizontal sectional elevation on the line 7—7 of Fig. 6;

Fig. 8 is a fragmentary elevational view 55 of the side of the oven illustrated in Fig. 5.

The same characters of reference indicate the same parts throughout the several views.

Referring now more particularly to Figs. 1 and 3, which illustrate diagrammatically 60 one example of carrying out the invention, the reference numeral 10 represents a coking chamber of an oven battery, said coking chamber being one of a plurality of coking chambers elongated transversely with respect to the battery and disposed in alternation with transversely-elongated heating walls provided with the usual flame flues for supplying heat to coke the charges within such coking chambers. It will, of 65 course, be understood that the ovens shown in the drawings may be fired with their own gas or other gas by developing the coking heat extraneously of the charge, and not by combustion within the coking chamber as in bee-hive practice. In this instance, the heat is developed in the flame flues in the heating walls along the sides of each coking chamber. The coking chambers 10 are charged with the coal, or other carbonaceous material to be coked, through charging holes 11 provided in the tops of the respective coking chambers, and the gases and by-products distilled from the coking charges in such chambers pass out through 80 ascension pipes 15 respectively communicating with the coking chambers through their tops. The several ascension pipes 15 lead to a collecting main 17 through which the distillates are conveyed for subsequent treatment in by-product recovery apparatus. As 85 shown, the flow through the individual ascension pipes 15 into the collecting main 17 is controlled by means of valves 16. Each coking chamber 10 is closed on its opposite sides by coke oven doors 13 and 14, which are removed when the coke is ready for pushing. The charge of coal introduced into the coking chamber 10 is leveled by means of a leveling device inserted through 95 a leveling hole on one side of the oven battery and normally closed by a closure element 12.

In accordance with the invention, after the distillation within each coking chamber 10 has been in greater part completed, the valves of the ascension pipes 15 corresponding to such chambers are closed, so

that such coking chambers are cut off from communication with the collecting main. The flow of the distillates is then reversed, and instead of drawing off the distillates 5 from the top of the coking charges the distillates are drawn off from the bottom through pipes 20 connected to the lower portions of the doors 14 located on the opposite side of the battery from the ascension 10 pipes 15, as shown in Figs. 1 and 2. These pipes 20 lead to and are connected by means of coupling elements 23 and 22 with a main 21 which extends along the battery of coking chambers. Preferably, steam is introduced 15 into each coking chamber 10 coincident with the reversal in flow of the distillate and the steam is supplied from a steam main 19 which runs parallel with the collecting main 17 and is provided with 20 valve-controlled injectors 18 respectively leading into the ascension pipes 15. These injectors 18 are opened when the valves 16 of the ascension pipes are closed, and the steam introduced into the lower portions of 25 such ascension pipes passes into the tops of the coking chambers in which the distillate flow is reversed and said steam thence flows downwardly through the charge along with the distillate and passes out of the coking 30 chambers through the outflow pipes 20.

In order that the vapors and gases which flow downwardly through the charge during the period of reversal may pass out of the charge uniformly and without hindrance, 35 a special channel may be made in the bottom of each charge after it has been introduced into the oven. Referring to Fig. 3, this channel may be formed in the following manner: through an opening 25 in the 40 lower portion of each door 13 on the pusher side of the oven battery, a channel forming rod 26 is inserted after the introduction of each charge to be coked. This rod 26 is conveniently carried by and operated by means 45 of the pusher machine 27 and may be pushed into the bottom of a coking chamber by means of a pusher bar which slides between guide rollers 30 and is operated forwardly and rearwardly through the medium 50 of suitable gearing 28. The channel forming rod 26 may be connected with the pusher bar by means of a coupling 29, and after having been introduced into and beneath the charge of coal in a coking chamber the rod 55 26 is disconnected from the pusher bar and permitted to remain in the coking chamber until the coking of the coal in the lower portion of the chamber has progressed sufficiently to render the walls of the charge 60 that engage the sides and top of the rod sufficiently firm to permit withdrawal of the rod without said walls collapsing. As the pusher machine can be detached from the channel forming rod, the pusher machine 65 may be moved away from a coking chamber

during the formation of the channel in the bottom of the charge and employed for other purposes. As soon as the walls of the channel formed by the rod 26 have hardened sufficiently, the rod 26 is withdrawn leaving a 70 channel through which the gases and vapors on reversal of the flow may pass freely to the outflow pipe 20.

In the case of ovens that are fed with coals, which are compressed or stamped before being introduced into the oven, the flues or exit channels in the bottom of each charge are formed by means of the device shown in Fig. 4. Referring to said figure, the charge to be introduced in the oven is compressed outside of the oven on a plate 31 formed with a rib 32 corresponding with the size of the channels to be made in the bottom of the charge. Suitable gearing may be provided in the hollow of this rib 32 for introducing the plate 31 on which the charge is supported into the oven, and for withdrawing the plate when the coking of the charge has progressed sufficiently to harden the walls of the channel formed in the bottom. 90

In the construction of by-product ovens for manufacturing coke for metallurgical purposes, the paramount object has always been to obtain the greatest possible equality 95 of distribution of heat through the heating walls, and this is done by evenly distributing the gas and air over the bottoms of the heating walls before combustion takes place and by causing the flames that result from the 100 combustion to extend throughout the various flame flues of each entire heating wall. But even with a high degree of equal distribution of heat through the heating walls, perfect equality in distribution through the 105 charge is impossible in practice owing to the nature of the charge itself. The charge of coal necessarily increases more or less in section toward the coke side of the oven to permit pushing of the finished coke out of 110 the oven. Moreover, local irregularities in the progress of the coking process exist from the beginning of the distillation or crop up during the working. Therefore, the progress of coking does not proceed in all portions of the charge at the same rate, so that by the time certain portions of the charge 115 have been completely coked, other portions of the charge may be under done and in order to complete the coking of such under done portions of the charge it will be necessary to over coke other portions of the charge. If the charge be not pushed out of the coking chamber, until all portions thereof have been completely coked, portions of 120 the charge may be subjected to excessive heating and over coking, which sometimes can only be avoided by pushing the charge without completely coking the under done 125 portions.

Excessive heating of the coke results not only in the expulsion of nearly all traces of hydrogen, but also in a change of the physical structure of the coke which makes it difficult to burn. This is a decided disadvantage in blast furnace operations for the reason that in blast furnace operations coke is required which is immediately reduced to carbon monoxide at the tuyers in order to get the greatest benefit out of the fuel and to prevent the fire from creeping up the charge in the blast furnace and causing scaffolding of the masses in the furnace and other troubles.

15 In accordance with the present invention an evening out of the temperature differences and restricting of the coking time are accomplished by cutting off communication between the coking chamber and the collecting main, when the distillation of the charge in said chamber has been in greater part completed and then conducting the vapors or gases downwardly through the coked charge taking them off at the bottom. The 20 vapors or gases, in passing downwardly through the charge have a cooling effect on the hotter portions of the charge which are located at the bottom, and a local circulation is induced which causes the heat to 25 pass from the hotter portions to the relatively cooler portions of the charge which are located generally at the top, thereby effecting transfer of heat from the hotter zones to the cooler zones and not only preventing over coking in the hotter zones but also accelerating the coking of the under done portions of the charge in the cooler zones and thereby restricting the coking time. In 30 addition to this, the downwardly streaming atmosphere, such as steam, or some other extraneously derived vapor or gas, results in the induction of an endothermic reaction effect on the hotter portion of the charge, thereby consuming much heat which otherwise would effect over coking. An additional result of the water gas reaction when steam is employed is an increase in the ammonia yield. Preferably the reversal in 35 flow of the distillate is started when the temperature peaks of the charge, wherever they may be located therein have risen above about 750° C.

40 As shown in Fig. 2, another measure may be advantageously carried out concurrently with the reversal in flow of the vapors and gases. In the space above the charge, in which the distillate collects, dissociation is liable to occur because of the high temperatures. This can be avoided by introducing 45 into the collecting space of coking chambers, before the reversal, the gases and vapors derived from other coking chambers in which the reversal of flow is being effected. This may be accomplished by connecting the 50 main 21 with inlet pipes 24 which lead into

the tops of the coking chambers. The coupling elements 23, as shown in Fig. 2, are designed to connect with either the pipes 20 or the pipes 24. The vapors and gases drawn off from the bottoms of certain coking chambers may then be introduced into the tops of others in which the coking process is proceeding and such introduced vapors and gases mingle with the distillate which collects in the gas collecting space 75 and effect a rinsing out of the newly formed gases, as well as a cooling, both of which factors combine to retard dissociation.

Another very remarkable effect, which is due to the timing of the above operations, 80 will now be described: if, in accordance with the present practice, all the ovens and distillation chambers are kept in communication with the gas collecting main from the first to the last hour of operation, the pressure in the coking chamber drops from 2 to 3 millimeters of water above zero, to 1 to 2 millimeters below zero. This is due to the considerable decrease of the quantity of gas produced per unit of time, and to the buoyancy caused by the heating up of the charge. 85 By this decrease of pressure in the chamber, an inflow of burnt gases through the heating walls and of air through the luting of the oven doors, which are often leaky, is 90 caused, so that the nitrogen contained in the distillation gases amounts to only a few per cent. at the beginning of the coking process, but rises considerably toward the end of this process.

Now if, in accordance with the special measure described above, all of the ovens are connected to the gas collecting main only for, say, the first twelve hours, while the steam gas mixtures of the ovens, which are 105 cut off from the gas collecting mains and are being subjected to the heat equalizing process, are led into the ovens in which the coking process has been going on for more than twelve hours, an excellent balancing of pressure will be obtained. As a small excess of pressure is thus always maintained in all the ovens of a battery, a deterioration of 110 the quality of the gas by the drawing in of nitrogen will be obviated. It is, however, 115 expressly remarked here that the times mentioned are relative times which are only stated in order to make the fundamental idea of the invention clearer by an example.

From the channels or flues made at the sole of the oven for the purpose of drawing off the mixture of steam and gas in the manner described above, some further advantages accrue which are of special practical importance:

If channels were cut in sole of the oven so as to lead into the chamber with the known passages or holes through which vapors are introduced for other purposes, these holes would be certain to be choked up 130

during working, and they would thus become useless. The same thing would happen if a special perforated pipe were always inserted in the charge at the sole of 5 the oven, and besides a pipe of this kind would, of course, be soon worn away. But by making a fresh channel in each new charge itself in the manner described, a 10 sort of counterpart to the gas collecting space formed at the top of the charge by the leveling process is obtained, so that the penetration of the coked charge by parallel streams of vapors or gases flowing from the top to bottom is secured.

15 In the form of the invention illustrated in Figs. 5 to 8 inclusive, there is formed in the bottom of each coking chamber an outflow duct 31 leading to a chamber 32 connected by means of a cross-duct 33 with a vertical 20 outflow channel 34 formed in the jamb brick of the heating wall. This vertical outflow channel 34 extends upwardly to a valve-controlled ascension pipe 35 that leads into an auxiliary collecting main 36, located beneath 25 the usual collecting main. The gas chamber 32 of each coking chamber may be reached through an inspection hole 37 normally closed by a plug 38. The reversal process carried on in the apparatus illustrated in 30 Figs. 5 to 8 inclusive proceeds exactly in accordance with the principles hereinabove described. In operation, the leveling rod will cover the gas or distillate outflow duct and prevent coke from falling in and clogging 35 said duct while the walls of the channel in the bottom of the coke are being formed. After the channel walls have hardened the leveling rod is removed and the walls themselves will prevent pieces of coke from falling into and 40 clogging the duct.

The invention as hereinabove set forth may be practised in various ways without departing from the scope of the claims hereinafter made.

45 I claim:

1. The improvement in the art of coking carbonaceous material, such as coal, which consists in applying an extraneously-developed coking heat to a mass of such material, 50 withdrawing the distillate in one direction from the coking charge of such material, until the distillation of the mass of such charge has been in greater part completed, and then, 55 during the continuance of the coking, withdrawing the distillate in the opposite direction from the said coking charge and, by such reversal in flow of the distillate through the coking charge, cooling the hotter regions of the coking charge to retard over-coking 60 thereof, while completing the coking of the cooler portions of the charge; substantially as specified.

2. The improvement in the art of coking carbonaceous material, such as coal, which 65 consists in applying an extraneously-devel-

oped coking heat to a mass of such material, withdrawing the distillate from the top of the coking charge of such material, until the distillation of the mass of such charge has been in greater part completed, and then, 70 during the continuance of the coking, withdrawing the distillate from the bottom of the coking charge and, by such reversal in flow of the distillate through the coking charge, cooling the hotter regions of the coking charge to retard over-coking thereof, 75 while completing the coking of the cooler portions of the charge, substantially as specified.

3. The improvement in the art of coking 80 carbonaceous material, such as coal, which consists in applying an extraneously-developed coking heat to a mass of such material, withdrawing the distillate in one direction from a coking charge of such material, until the distillation of the mass of such charge 85 has been in greater part completed, and then, during the continuance of the coking, reversing the direction of flow of the distillate through the coking charge, and, by such reversal, cooling the hotter regions of the coking charge to retard over-coking thereof, 90 while completing the coking of the cooler portions of the charge; substantially as specified. 95

4. The improvement in the art of coking 100 carbonaceous material, such as coal, which consists in applying an extraneously-developed coking heat to a mass of such material, withdrawing the distillate in one direction from the coking charge of such material, until the distillation of the mass of such charge has been in greater part completed, and then, 105 during the continuance of the coking, passing gas in the opposite direction through the coking charge and, by such reversely flowing gas cooling the hotter regions of the coking charge to retard over-coking thereof, while completing the coking of the 110 cooler portions of the charge; substantially as specified.

5. The improvement in the art of coking 115 carbonaceous material, such as coal, which consists in applying an extraneously-developed coking heat to a mass of such material, withdrawing the distillate in one direction from the coking charge of such material, until the distillation of the mass of such charge has been in greater part completed, and then, 120 during the continuance of the coking, passing vapors in the opposite direction through the coking charge and, by such reversely flowing vapors cooling the hotter regions of the coking charge to retard over-coking thereof, while completing the coking of the 125 cooler portions of the charge; substantially as specified.

6. The improvement in the art of coking 130 carbonaceous material, such as coal, which consists in applying an extraneously-devel-

oped coking heat to a mass of such material, withdrawing the distillate in one direction from the coking charge of such material until the temperature peaks of the mass of such charge have been elevated above substantially 750° C., and then, during the continuance of the coking, withdrawing the distillate in the opposite direction from the said coking charge and, by such reversal in flow 10 of the distillate through the coking charge, cooling the hotter regions of the coking charge to retard over-coking thereof, while completing the coking of the cooler portions of the coking charge; substantially as specified.

7. The improvement in the art of coking carbonaceous material, such as coal, which consists in applying an extraneously-developed coking heat to a mass of such material, 20 withdrawing the distillate in one direction from the coking charge of such material, until the temperature peaks of the mass of such charge have been elevated above substantially 750° C., and then, during the continuance of the coking, passing vapors in the opposite direction through the coking charge and, by such reversely flowing vapors cooling the hotter regions of the coking charge to retard overcoking thereof, while completing 25 the coking of the cooler portions of the charge; substantially as specified.

8. The improvement in the art of coking carbonaceous material, such as coal, which consists in applying an extraneously-developed coking heat to a mass of such material, 35 withdrawing the distillate in one direction from the coking charge of such material, until the distillation of the mass of such charge has been in greater part completed, and then, 40 during the continuance of the coking, passing a mixture of distillate and steam in the opposite direction through the coking charge and thereby cooling the hotter regions of the coking charge to retard over-coking thereof, while completing 45 the coking of the cooler portions of the charge; substantially as specified.

9. In a coking retort oven, in combination: a coking chamber for receiving a 50 charge of material such as coal to be coked, gas off-take means at the bottom of said coking chamber, and means for forming and establishing in the bottom of the charge introduced into such coking chamber a gas 55 outflow channel in registry with said gas off-take means, substantially as specified.

10. In a coking retort oven, in combination: a coking chamber, heating walls contiguous to said coking chamber for supplying 60 an extraneously-developed coking heat to a mass of carbonaceous material, such as coal, within said coking chamber, distillate outflow means at the top of said coking chamber, distillate outflow means at the bot-

tom of said coking chamber, and means for 65 withdrawing distillate from said coking chamber through either of said outflow means; substantially as specified.

11. In a coking retort oven, in combination: a coking chamber, heating walls contiguous to said heating chamber for supplying extraneously-developed coking heat to a mass of carbonaceous material, such as coal, within said coking chamber, distillate outflow means at the top of said coking 70 chamber, distillate outflow means at the bottom of said coking chamber, means for withdrawing distillate from said coking chamber through either of said outflow means, and means for injecting steam into said coking 75 chamber; substantially as specified.

12. In a coking retort oven, in combination: a coking chamber, heating walls contiguous to said coking chamber for supplying an extraneously-developed coking heat 85 to a mass of carbonaceous material, such as coal, within said coking chamber, distillate outflow means at the top of said coking chamber, distillate outflow means at the bottom of said coking chamber, means for withdrawing distillate from said coking chamber through either of said outflow means, and means, located at the top of the coking 90 chamber, for injecting steam into said coking chamber, substantially as specified.

13. The improvement in the art of coking carbonaceous material, such as coal, which consists in applying extraneously-developed coking heat to a mass of such material, withdrawing the distillate in one direction from 100 the coking charge of such material, and, when the outside surfaces of the coking charge have been elevated above substantially 750° C. and during the continuance of the coking, withdrawing the distillate in the 105 opposite direction from the coking charge and, by such reversal in flow of the distillate through the coking charge, completing the coking of the mass of such charge without over-coking of the outside surfaces 110 thereof; substantially as specified.

14. The improvement in the art of coking carbonaceous material, such as coal, which consists in applying an extraneously-developed coking heat to a mass of such material, 115 withdrawing the distillate in one direction from the coking charge of such material and, when the outside surfaces of the coking charge have been elevated above substantially 750° C. and during the continuance of the coking, passing vapors in the opposite direction through the coking charge and, by such reversely flowing vapors, completing the coking of the charge without over-coking 120 of the outer surfaces thereof; substantially as specified.
